UNITED STATES PATENT OFFICE.

CHARLES M. CARTER, OF CUMING CITY PRECINCT, NEBRASKA, ASSIGNOR
OF ONE-HALF TO ALFRED E. CARTER, OF HAVANA, CUBA.

DESIGN FOR A PLOW-SHOVEL.

SPECIFICATION forming part of Design No. 34,795, dated July 16, 1901.

Application filed June 4, 1901. Serial No. 63,173. Term of patent 14 years.

To all whom it may concern:

Be it known that I, CHARLES M. CARTER, a citizen of the United States, residing in Cuming City Precinct, in the county of Washington and State of Nebraska, have invented and produced a new and original Design for Plow-Shovels, of which the following is a specification, reference being had to the accompanying drawings, forming part thereof.

Figure 1 is a front elevation showing my new design. Fig. 2 is a side elevation. Fig. 3 is a top or plan view, and Fig. 4 is a cross-section on the broken line 2 of Figs. 1, 2, and 3.

As shown in the drawings, the leading and material features of my design comprise a plate consisting of a lower forward narrower portion 5, having parallel side edges 2 and 2' and bent upward from the point 4 in a curve of horizontal axis throughout its width and 20 merged into an upper wider portion 6 by the

outward lateral and backward curvature of the edges 2 and 2' to meet the edges 3 and 3', which recede from the front, the upper wider portion 6, bent in a curve of oblique axis, standing in a plane at right angles to the axis 25 of the curve of the lower forward narrower portion 5.

Having described my invention, what I claim as new, and desire to secure by Letters Patent, is—

The design for a plow-shovel, as herein shown and described.

In testimony whereof I have signed my name to this specification in the presence of two subscribing witnesses.

CHARLES M. CARTER.

Witnesses:

W. S. CARTER,
SAMUEL WARRICK.
